UNITED STATES PATENT OFFICE.

WILLARD J. FENDNER, OF PITTSBURGH, PENNSYLVANIA, ASSIGNOR TO CLARK CAR COMPANY, A CORPORATION OF PENNSYLVANIA.

FLUID-PRESSURE SYSTEM.

Application filed September 9, 1920. Serial No. 409,192.

To all whom it may concern:

Be it known that I, WILLARD J. FENDNER, a citizen of the United States, and a resident of Pittsburgh, in the county of Allegheny and State of Pennsylvania, have made a new and useful Improvement in Fluid-Pressure Systems, of which the following is a specification.

My invention relates to railroad rolling stock and in particular to dump cars operated by fluid pressure such as compressed air. The mechanism by which the car doors are secured and operated and the car dumped may vary and those familiar with the art are aware of the multitude of dumping mechanisms now in existence. The particular mechanism used is unimportant as my invention consists in the fluid pressure control system. I refer to U. S. Letters Patent No. 1,333,293, Clark et al., March 9, 1920, for a detailed disclosure of a tilting body dump car provided with side doors hinged near the body floor and in which the body is released from an upright position 25 and tilted to one side and the doors on that side opened to dump the load. The body is subsequently returned to and secured in upright position and the doors closed. All of these operations are performed automatically by control of compressed air.

My system disclosed herein has been applied to a car of the above type and in the drawing accompanying this specification and forming part thereof the arrangement 35 of the piping and apparatus is adapted for such a car which car is indicated in part by dot and dash lines.

Figure 1 is a side elevation of the system in place on the car; Fig. 2 is an elevation, 40 on a larger scale, of either end of the car and as much of the system as is located thereon; Fig. 3 is an enlarged side elevation adjacent the transverse center line of the car; Fig. 4 is a plan of the apparatus 45 and piping shown in Fig. 3; Fig. 5 is a view on line 5—5 of Figs. 1 and 3 and showing a part of the body and door control mechanism; Fig. 6 is a view on line 6—6 of Fig. 4, and Fig. 7 is a side elevation of apparatus and piping omitted from Fig. 1 50 to more clearly disclose parts located in the rear thereof. Fig. 8 is a sectional view illustrating a valve and valve-operating mechanism such as disclosed and claimed in

Clark Patent No. 1,373,599 of April 5, 1921. 55

The car underframe A is mounted on the usual trucks and has upstanding ends B between which, and tiltingly mounted on the underframe, is the body C. The sides of the car are formed of doors D which are so 60 hinged to the underframe and body that tilting of the body to one side swings the doors on that side to an open position where they form an extension of the car floor. The body is normally locked in an upright 65 position and when the car is to be dumped, it is first necessary to release the door latching mechanism and to then tilt the body to the dumping position.

The locking mechanism on the left hand 70 side of the body is mounted on a locking shaft E (Fig. 5) and is released by rotation of the shaft in a clockwise direction. The body is then tilted to the right by being pushed sideways at both of its ends. This 75 rotation of shaft E and the pushing of the body is accomplished by the following apparatus:

A reservoir tank 1 is mounted on the underframe A and is supplied with air by 80 the thru train line supply line 2 thru a union T 3, a connecting pipe 4, having a dust collector 5, (Fig. 7) a check valve 6 and a cut-out cock 7 and entering the reservoir 1 thru a union T 8 and a branch 9. 85

A latch operating cylinder 10 is mounted on underframe A between the underframe sills and displacement of its piston 11 (Fig. 5), thru levers F and G, rotates latching shaft E. To operate cylinder 10, air passes from reservoir 1 thru a car operating line 12 (Figs. 1 and 2) to valve 13, from where it is controlled manually, to piping 14 which unites with a thru train operating line 15 leading thru a union T 16 (Fig. 4) and a 95 cut-out cock 17 to the latch shaft operating cylinder 10. Valve 13 is controlled by a handle 24.

When piston 11 has been thrust to its lowermost position, it has operated to release 100 the latch mechanism and it uncovers a port 18* in the wall of cylinder 10 which leads thru piping 18 to a reservoir operating valve 19 (described and claimed in United States patent to Clark, No. 1,373,599 of April 5, 1921, which is thereby automatically opened permitting the air in reservoir 1 to pass thru piping 20 directly to both

ends of the car where it is admitted, thru a relief valve 21 (forming the subject matter of a copending application, Serial No. 345,669, Clark et al., filed December 17, 1919,) to the body tilting cylinders 22. These cylinders are pivotally mounted upon the underframe upstanding ends B and their piston rods 23 are adapted to engage the side of the body end. By swinging the 10 cylinders 22 on their trunnions 22^a, their piston rods may be positioned to engage the opposite side of the car to tilt the body in the opposite direction.

When the load is dumped, control valve 15 13 is turned to close line 12 and to connect piping 14 with an atmospheric-exhaust (or the air in the thru train operating line 15 is exhausted at a remote point by the operator) and the action of spring H raises piston 20 11. The supply of operating air thru port 18^a being terminated, and the rising piston 11 reducing the pressure in line 18, valve 19 automatically closes the passage from reservoir 1 to pipe 20 and opens an exhaust 25 port 25 which permits the operating cylinders to exhaust therethru and their pistons telescope and the car body is returned to upright position by the relative position of the center of gravity and the pivotal point of 30 support on the underframe as disclosed in co-pending application Serial No. 256,130, Clark, filed September 28, 1918.

The valve 19 and its operating mechanism is disclosed in Fig. 8. As there shown, 35 the valve proper controls the delivery of actuating fluid through the ports *a* and *b*, the port *a* communicating with the source of fluid pressure and the port *b* with the dump cylinders. The valve casing is formed 40 integrally with a valve-operating cylinder in which a differential piston *d* is located. This cylinder is provided with the exhaust port 25 which is so located that the port *b* is in open communication with the port 25 45 when the piston *d* is in such a position that the valve 19 is closed. The lower end of the cylinder is provided with a port *e* which communicates with the latch-operating cylinder 10 through the piping 18. Valve 19 50 is provided with a spring for holding it to its seat and the piston *d* is provided with a spring for assisting the valve-closing movement of the piston.

To tilt the heavy body requires a large 55 amount of work. This requirement is accentuated by the uneven path of travel for the body on the underframe, as detailed in application Serial No. 256,130, Clark, filed September 28, 1918, which creates a peak 60 load on cylinder 22 at the beginning of its movement. To carry this load and to provide for the large piston displacement and to avoid excessive friction in connecting piping and abnormally large air pressure 65 in reservoir 1, a relatively large piping from

the reservoir to cylinders 22 is necessary compared with that required for cylinder 10 and valve 19.

To use the same piping for cylinders 22 and for cylinder 10 means either a too violent thrust and sudden stopping of piston 11 in cylinder 10 and the mechanism operated thereby with destruction of piston packing, bearings and high air friction, or, a slow, inefficient operation of cylinders 22 75 and the car body, if operated at all. My construction avoids these difficulties while utilizing the advantages of a single manual control of the operating line and automatic control of the car dumping mechanism. The 80 piping arrangement shown enables me to install any appropriate size of pipe for the control line and any different size pipe desired for the operating line. This arrangement could not be followed with any previously used system with which I am familiar.

I claim:—

1. In combination with a tilting body dump car having a latch operating mechanism for locking the body in an upright position, a dump cylinder operatively connected to the body, a latch operating cylinder having an inlet port and a piston controlled fluid delivery port, a piston operating therein and operatively coupled to the latch operating mechanism, a source of fluid pressure, an automatic valve for controlling delivery of fluid from said source to said dump cylinder and for exhausting said dump cylinder, a valve operating cylinder connected to the delivery port of said latch operating cylinder, a valve operating piston located in said valve operating cylinder for actuating said automatic valve, and a manually operated valve for controlling the delivery of fluid from said source to said latch operating cylinder and the exhaust of fluid from said latch operating cylinder.

2. In combination with the tilting body of a dump car and the latch operating mechanism for holding the body in an upright position, a latch operating cylinder having a combined inlet and discharge port, and a piston controlled fluid delivery port, a dump cylinder having a combined fluid inlet and discharge port, a source of fluid under pressure, an automatic control valve for controlling the delivery of fluid to and the discharge of fluid from said port of said dump cylinder, a valve operating cylinder communicating with the fluid delivery port of said latch operating cylinder, a piston located therein for operating said automatic valve, and a manually operated valve for controlling the delivery of operating fluid to and the discharge of operating fluid from the combined inlet and discharge port of said latch operating cylinder.

3. In combination with the tilting body

- of a dump car having a latch-operating mechanism for locking the body in an upright position, a dump cylinder operatively coupled to the body, a latch-operating cylinder having a piston-controlled fluid delivery port, a piston operating in said cylinder to open and close said delivery port, a source of fluid under pressure, a manually-controlled valve for delivering fluid under pressure to said latch cylinder, a separate valve for establishing and cutting off direct communication between said source of pressure and said dump cylinder, a co-operating cylinder and piston for actuating said valve and for controlling the exhaust of operating fluid from said cylinder, and means for delivering fluid from said latch-operating cylinder to operate said last-mentioned piston.
- 20 4. In combination with the tilting body of a dump car, a latch-operating mechanism for locking the body in an upright position, a dump cylinder operatively coupled to the body, a latch-operating cylinder having a piston-controlled fluid-delivery port, a fluid responsive piston located within said cylinder for controlling the delivery of fluid through said port, a source of fluid under pressure, a manually-controlled valve for controlling the delivery of fluid from said source to said cylinder and the discharge of fluid from said cylinder and a separate valve mechanism responsive to variations in fluid pressure within said latch cylinder for establishing and cutting off direct communication between said source of pressure and said dump cylinder and for exhausting said dump cylinder.
- 25 5. In combination with the tilting body of a dump car, a dump cylinder operatively coupled to said body, a source of fluid under pressure, an automatic valve for controlling the delivery of fluid from said source to said cylinder and the discharge of fluid from said cylinder, a valve-operating cylinder, a fluid-pressure-actuated valve-operating piston located in said cylinder, a second cylinder of greater volumetric capacity than said valve-operating cylinder and having a piston-controlled port formed therein for establishing communication with said valve-operating cylinder, a fluid pressure controlled piston operating within said second cylinder for controlling said port to admit fluid under pressure to said valve-operating cylinder and for reducing the pressure within said valve-operating cylinder while moving in response to a reduction in fluid pressure, and a manually controlled valve for controlling the delivery of fluid from said source to said second cylinder.
- 30 In testimony whereof, I have hereunto subscribed my name 31st day of August, 1920.

WILLARD J. FENDNER.
